UNITED STATES PATENT OFFICE.

THOMAS C. SPELLING, OF CHICAGO, ILLINOIS.

PRINTING PRESS.

Application filed August 13, 1927. Serial No. 212,819.

This invention relates to certain new and useful improvements in printing presses and deals particularly with that type of apparatus which is used for producing so-called "form letters". Usually letters of this character are first printed upon a press or multigraph machine, leaving space for the addressee's name, address and salutatory blank. This blank space is afterwards filled in on a typewriter and usually the type of the typewriter machine is of a different character or of a different impression than that of the body form of the letter. In other instances slugs carrying a type impress of the name, address and salutation are used. In still another instance, an attempt was made to make the bodies of letters on a plurality of mechanically operated typewriters and then insert the name, etc. with the same kind of hand operated typewriter. But it was found that the difference between results of impressions were clearly apparent upon casual inspection. In either case the letter, as a whole, is given unsightly form which is quickly noticeable by the differentiating features as to the filled-in part of the letter in comparison with that of the printed form. It is therefore the principal object of the present invention to overcome these difficulties by producing a machine wherein a little chase containing type identical with that set up in the letter chase is fed into its proper position between the body of the letter and what is commonly known as the letter head, so as that the name of the addressee, his address and the proper salutatory are printed simultaneously with that of the set up form. The type employed in the little chase is identical with that in the letter form, hereinafter designated as the letter chase. By giving the letter made up in this fashion a simultaneous impression, the whole letter below the letter head will have a uniform appearance. It is notable that full advantage is here taken of the fact that type foundries now manufacture and sell what is known as standardized typewriting type.

Another object of the invention is the provision of mechanism with which the little chases are successively fed into position in the form letter, whereby it becomes practicable to print with one and the same cycle of press movement all of the letter including the letter head.

Another object of the invention resides in the novel manner in which little chases are fed from a galley into their proper position in the form letter.

Other objects and aims of the inventions, more or less broader than those stated above, together with the advantages inherent, will be in part obvious and in part specifically referred to in the course of the following description of the elements, combinations, arrangement of parts and application of principles constituting the invention, and the scope of protection contemplated will appear from the appended claims.

In the accompanying drawings, which form a part of this specification, similar figures of reference indicate like parts throughout the several views in which:

Fig. 1 is a plan view.

Fig. 2 is a vertical longitudinal cross-section on line 2—2 Fig. 1.

Fig. 3 is a cross-section taken at right angles of Fig. 2 in line 3—3 Fig. 1.

Fig. 4 is a plan section of the mechanism below the press bed, taken in line 4—4 Fig. 2.

Fig. 5 is an enlarged fragmentary plan of track and little chase gripping device by which little chases are shifted forward in the galley and slot in letter chase.

Fig. 6 is an enlarged vertical fragmentary section showing little chase gripping mechanism, similar to Fig. 2.

Fig. 7 is an enlarged fragmentary plan of the recess in floor of galley, slot therethrough and sliding plate occupying same.

Fig. 8 is an enlarged plan view of a little chase.

Fig. 9 is a bottom view of the little chase.

Fig. 10 is an enlarged side elevation plan of a little chase.

Fig. 11 is an enlarged longitudinal section of plan of a little chase taken on line 11—11, Fig. 8.

Fig. 12 is an enlarged cross-section of a little chase, taken in line 12—12, Fig. 8.

Fig. 13 is an enlarged detail of stationary arm.

The mechanical result sought is the displacement from proper position in a letter chase, after the print impression thereon has been made, of a little chase containing type for the name, address and proper salutatory of one individual, firm or corporation with another little chase containing those of

another, which takes the former's place at each completed movement of the press, and to do this successively without limit.

It will be noted that the letter chase consists of two separate parts, one part on either side of a passage-way for the little chases, the passage-way being hereinafter referred to as the slot, 11. In the narrower of the two parts, designated 12, will be set the type 10 for printing the letterhead, in any proper type, and under it, properly related, the date. In the other part, 13, is set the type for the body of the letter, and of course the signature may be also printed, if a suitable cut 15 therefore be provided. The letterhead may be set in any type suitable for letterheads, and it may be printed with the same print impression that prints the name, address and salutatory and body or text of the letter.

20 In hereinafter referring to the "letter chase", the term is to be understood to include both the parts, 12 and 13. Those parts must be securely fastened to the press bed, 31. For this purpose various means might 25 be suggested, some of which might involve modification of the press bed and exterior parts of the letter chase, for instance rods with suitably formed ends and proper openings for their insertion.

30 The space between the interior walls of letter chase, between which is slot, 11, is of sufficient width to allow the passage between them with frictional engagement of resilient wings, 47, of the little chases, 14. The 35 thickness of the bases of each of the parts 12 and 13 is exactly the same as that of the ungrooved portions of these little chases. It will be noted that the slot, 11, extends less than half the width of the letter chase, and 40 terminates at the margin of an opening, 32^a, through the press bed. Suitably attached at the inner margin of this opening, to the nether surface of the press bed, is the slanted chute 15, on which each ejected little chase 45 slides before falling to the floor of the press room, or into a receptacle, the purpose of providing the slanted chute, 15, being the breaking of the force of the fall of the little chases and prevention of resulting injury to the type carried therein.

50 In practice, it is necessary to construct the containing walls of letter chase, adjacent to this opening, thinner than the portions thereof adjacent to the integral section 55 of the slot, so that the little chases may freely fall, through the opening. Hence the shoulders, 16, to indicate an exterior diminution of the thickness of the two walls between which that section of the slot extends. To 60 have the opening also a little longer than the integral base of the slot presents no problem.

65 As will be hereinafter seen, a shifting and propulsive mechanism is provided which will exert force against the bases of the little

chases upwardly as well as forward. Hence the wings, 47, the functions of which are to have movement under the downwardly face shoulders, 46 (best shown in Fig. 3), and to tighten the little chases in the slot in the printing process.

Below the horizontally positioned downwardly faced shoulders, 46, will move the wings, 47. A glance at the horizontal portion of the galley, 48, discloses that the same shoulders are extended and appear therein almost to the junction of horizontal and slanted portions of the galley, 48 and 48^a respectively. At the point where the shoulders terminate, in the horizontal portion they are curved slightly upward, the purpose of which is to allow the little chases, equipped with the wings, 47, to be freely and without being caught on any sharp angle pushed under them by the propulsive force provided for as hereinafter explained. The formation of the shoulders, 46, results in a reduction below them of the thickness of the walls of the slot, and of the horizontal portions of the galley in which they are formed. Including the outward curves, 45, of the wings, the width of each little chase exceeds that of the slot; in other words, the compression of the wings, in 95 passage through the slot causes frictional engagement against the walls of the slot under the shoulders, because of the presence of curves, 45. The presence of the wings under the downwardly faced shoulders, 46, also preserves their level as against the force of the shifting device beneath them. The wings consist of narrow resilient metal strips attached to each exterior side wall of each little chase. These wings are suitably attached, near what may be designated the 100 front end of each side of each little chase, and are slightly curved outward, their unattached ends resting against the sides of the little chases.

105 The power of gravity combined with mechanical force is utilized in the invention, and, for its utilization, the inclined galley, formed from metal or other suitable material, is employed, as a feeder of the shifting device, being actuated by downward gravity 110 force. As will be noted, the galley is formed with a gradual curve near the lower end of the slanted portion, 48^a, the curve merging into the horizontal portion, 48. The terminal, 17, of the horizontal portion rests in an 115 indentation in the press bed to which it is secured by screws or bolts 56. Thus the inner bottom surface of the galley is made flush with that of the press bed.

120 It is obvious that the interior width of the galley must be slightly greater than that of the little chases. Down to the junction with the slot, the width suffices to allow the little chases to move freely, notwithstanding the 125 resilient wings, 47, thereon; but at the point 130

indicated by reference figure 16^a the extreme tips of both sides of the terminal are slightly curved inwardly. That produces the frictional engagement with in the slot previously referred to.

The point of juncture of the galley and slot is further indicated by reference figure 21.

Each little chase, 14, minus the wings, 47, is about one and one-fourth inches of exterior width, and two and one-half inches in length, the walls extending about three-fourths of an inch high, above the base. To the length proper of each little chase must be added the protuberance 29, across what will function as the front end, serving to separate them for an essential operation, presently explained. The base of each little chase is grooved as shown at 18, leaving the narrow integral margins 19 and the projection, 20. The projection is, however, grooved down almost but not quite as much as the other grooving. An incision or gap, 28^a, is made in the rear part of this projection, to facilitate functioning of the shoulder and point 27 and 28 respectively.

In use, the type set in the little chases should be tightly confined. For this purpose, the thin rubber slips, 21^a, may be attached to the interior walls, at the sides and ends, and thin spacers, 21^b, placed, with pressure, between the rubber slips and type body. Other means could but need not be suggested.

In the upper side of the floor of the horizontal portion of the galley is the recess, 22, partly on each side of the slot, 23, both recess and slot of length equal to the length of two little chases. The sliding bar, 25, is connected by little rods or slabs with the shelf, 24, which has movement in the recess; and attached to the latter at one end is the spring, 26, extending backward and terminating in the point, 27, behind and above which is the shoulder, 28. It will be noted that the spring curves slightly upward near the point, the purpose of which is to insure frictional engagement of its shoulder on the rear end of a little chase. The grooving of the bases of the little chases above mentioned positions their front bases above the floor of the galley and allows room for the functioning of the spring and its point. As provision for the proper functioning of the spring, the aforesaid lateral protuberance, 29, is formed across the front exterior of each little chase, the purpose of which is to hold the ends slightly apart as they move forward. Obviously the shelf and spring member, 26, could be fabricated as a single piece of metal.

The shifting device just described is placed for operation, inside the casing, 30, (only the lower edge of it being exhibited) which is attached to the exterior surface of the base of the galley, and extends from

near the edge of the press-bed, the length of two little chases under the horizontal portion beyond that point. Inside this casing and on its floor, the sliding bar, 25, has movement. The casing is open at each end, to allow the movements, in and out, of the little chain, 54, attached to the coiled wire, 31^a, at the one end and of the little chain, 32, at the other, in operation. Abutting the casing, 30, is the larger and longer casing, 75 33, in which the coiled wire, 31^a, and little chain, 54, are shown. The coiled wire and its chain attachment are of capacity to perform the operations hereinafter assigned them. The wire is attached to the interior 80 of the closed end of casing 33, at one of its ends, and to the little chain, 54, at the other, which, in turn, is attached to the sliding bar, 25. The casing, 33, is supported on the sides of the galley, as shown in the drawing. 85 It will be noted that casing 30 extends slightly lower than the surface of the base of the press bed; also that both chains slant downward. Such positioning is necessary to the effectiveness of operation. Little 90 chain 32 extends out of the casing, 30, under the roller 34 and around the roller 35 where, for my present purpose, I break it, to facilitate illustration. These rollers are separately axled into downwardly extended supports 95 35^a. These rollers serve the first to bring the chain to a horizontal position, and the second to give it a right angled turn, which is seen to be necessary.

The sliding bar 25, the sliding shelf, 24, carrying the spring member, 26, connected by rods as shown, constitute a sliding frame whose width approximately equals the length of one little chase; but the casing, 30, must equal in width two little chases, 105 as must also the recess, 22, in the bed of the galley and the slot, 23, through which the connecting rods extend.

The arm, 36, is axled in the support 37, which is supported in stationary position, 110 on the floor of the press room under the press bed. But, in some instances, it will be found more convenient to provide support on inactive parts of the press bed. This arm has limited vertical movement on its axle for its free end, but when not actuated, is held in horizontal position by the resilient tongues, 40. The free end of the arm, when not actuated, rests, as seen in Fig. 13.

In Fig. 3, I have all that part of the little chain, 32, not shown in Fig. 2, stretched out at right angles to the part, shown in Fig. 2, as it will appear in use. It is here connected with the end of the lower part 41 of the sliding frame, the chain being extended to that connection through one of the supporting parts, 42 of the sliding frame. The sliding frame has movement, when actuated, one part on and the other part under, the girder, 43, the upper and lower parts of the sliding 125 130

frame being attached to each other by rods, 44, extending through a slot, 45^a, (only position indicated) the slot running through the girder from end to end. This frame, in operation, slides approximately the length of a little chase; consequently the length of the girder is required to be approximately the length of two little chases. Attached to a corner of the sliding frame, extended downward, and in a position to strike the arm 36 in the functioning of the parts, is the knob, 45^b. Properly supported on the nether side of the press bed, and held in such position that, as it is carried forward with the other parts, its slanted end will pass under arm 36, is the member, 46^a. It is rotatively pivoted on a horizontal extension of the support just referred to, but its range of downward movement is limited by a rigid arm, 46^b, supported on the end of the axle for member 46^a (said support not shown) the rigid arm 46^b shown extending into an under cut, 52. Said slanted end normally rests so that in the movement of the press bed forward the stationary arm, 36, will mount the slanted section, be struck by the knob 45^b, and passed under by the level section, 55, of member 46^a, until it is reached by the cam faced member 47^a, which disengages it from the knob the fractional part of an inch short of the knob reaching the limit of its movement. This cam faced member consists of its main support back of the sliding frame and a horizontal extension of said main support, the end of the extension being beveled as shown, right over the horizontal end, 55, of member 46^a, but out of the path of knob, 46^b. By contact with the cam faced member, the arm is disengaged and deflected downward and comes to rest in its normal horizontal position, through action of springs, 40. The arm now has no useful function until the press bed has completed another cycle of movement. But on the return trip the press bed and attachments must pass over the arm. This is provided for by the shape of said members, 46^a and 55. There could be no problem as to the part 46^a, because of its being heavier than the horizontal end and because of the method of its support above described. But to prevent the upper spring 40, on arm 36 pulling down the horizontal elevated end of member 46^a, thereby disengaging the knob, 45^a, prematurely, a support for that end, during its passage under the arm is provided. Just back of the girder for the sliding frame and its supports is another support attached to the press bed, and on that is the vertically positioned axle, 47^b, for the arm, 53, the end of which is, as seen in the drawing, at rest under the level end of member 46^a. At the side of the axle is the post 49. Fastened to that and the adjacent side of the arm, 53, is a coiled spring, 50, of only moderate pull power; but attached

to the post and resting against the same side of the arm is the rigid rod 51. It is obvious that the arm, 53, supports the level end during the forward trip. On the return trip, arm, 53, strikes arm 36 whereby arm 53 is swung out from under the horizontal end of member 46^a as the horizontal end is lowered by the passage of the slanted end of said member over the arm, 36. But instantly thereafter, all the parts assume their original normal positions, ready for a repetition of the performance. The rigidity of the rod, 51, brings arm 53 immediately to rest, in position as seen in the drawing and prevents its oscillating back and forth. All the supporting parts of the frame work for actuating parts just described, and wherein reference figures 41 to 55 inclusive are used are in turn supported on the nether side of the press bed.

Without dwelling upon minutiae, it will suffice to briefly state that the result of contact of the stationary arm 36 with the knob, 45^a, moves the sliding frame, 41 which in turn pulls the chain, 32, which actuates the sliding bar, 25. By these forces, the coiled wire 31^a, is stretched to the extent of the length of one of the little chases, or approximately two and one-half inches.

The main purpose is accomplished by the direct movement, namely, a little chase which has already received a print impression is ejected from slot, 11, and through propulsive force another is installed in its place. At the moment when the knob, 45^a, strikes the stationary arm, 36, the downward and forward movement of the file of little chases in the galley is obstructed by the frictional engagement of the wings, 47, with the walls of the slot, 11. But, when the spring, 26, is actuated by the operation of the mechanism just described, and the little chases just ahead of the shoulder, 27, of the spring are propelled forward, the little chase just back of it closely follows it, being pushed forward by the weight of the file of little chases behind it. By the reaction of all the parts during completion of the cycle of movement of the press bed, the spring point above the sliding bar resumes its position in space back of the next little chase shunted into place for it, and all is ready for the next contact between the stationary arm and the knob on the sliding frame.

Every lateral attachment to press and press bed may be detachably attached. And there is no known reason why a plurality of such equipments may not be attached to one press, or why this equipment will not fully function where the press is run at high speed.

Of course, care should be used in the adjustment of lengths and dimensions; but exactitude to a small fraction of an inch is

not essential. A margin of movement is afforded by the adaptability of coiled wire, 31^a, which, anyhow, should not entirely relax at any time. It should fall short of ⁵ action sufficiently to keep the little chain taut. Again there is no strict rule as to the position of name, address, etc. in a letter, only they should be somewhere on the left hand side. And, of course, the specification ¹⁰ 10 of length and width of the galley and little chases is not absolute. These and other matters are questions for mechanical construction. So here again, a slight non-adjustment would have no serious consequences.

¹⁵ 15 What I seek to secure by United States Letters Patent is:

1. In a machine of the character described, instrumentalities for guiding and placing a chase in printing position, the ²⁰ 20 guiding means having upstanding walls, and the chase having resilient means at one side thereof to create a firm engagement between the chase and guiding means.

2. In a machine of the character described, instrumentalities for guiding and placing a chase in printing position, the ²⁵ 25 guiding means having upstanding walls, and the chase having resilient means at opposite sides thereof to create a firm engagement ³⁰ 30 between the chase and guiding means.

3. In a machine of the character described, a chase having a bottom and upstanding side walls, and resilient means within the chase cooperating with said side ³⁵ 35 walls adapted to firmly hold printing means when inserted in the chase.

4. In a machine of the character described, a chase having a bottom and upstanding side walls, and resilient means ⁴⁰ 40 within the chase cooperating with said side walls adapted to firmly hold printing means when inserted in the chase, said resilient means comprising a compressible strip located adjacent the wall of the chase, and a ⁴⁵ 45 suitable spacing strip interposed between the compressible strip and the interior space of the chase to receive the printing means.

5. In a machine of the character described, a chase having a bottom and upstanding side walls, and resilient means ⁵⁰ 50 within the chase cooperating with said side walls adapted to firmly hold printing means when inserted in the chase, said resilient means comprising compressible strips located adjacent opposite walls of the chase, and suitable spacing strips interposed between the compressible strips and the interior space of the chase to receive the printing means.

6. In a machine of the character described, a chase, and means for propelling and guiding the same into printing position, the chase having depending flanges at its ⁶⁰ 60 opposite sides to provide a way therebetween at the bottom of the chase, a de-

pending lug on said bottom in said way, and a propelling means having an engaging part to cooperate with said lug, substantially as described.

7. In a machine of the character de- ⁷⁰ 70 scribed, a chase, and means for propelling and guiding the same into printing position, the chase having depending flanges at its opposite sides to provide a way therebetween at the bottom of the chase, a de- ⁷⁵ 75 pending lug on said bottom in said way, and a propelling means having an engaging part to cooperate with said lug, said engaging part being formed and adapted to recede past said lug for a succeeding portion after ⁸⁰ 80 the chase has been moved, substantially as described.

8. In a machine of the character described, a chase, and means for propelling and guiding the same into printing position, the ⁸⁵ 85 chase having depending flanges at its opposite sides to provide a way therebetween at the bottom of the chase, a depending lug on said bottom in said way, and a propelling means having an engaging part to cooperate ⁹⁰ 90 with said lug, said engaging part being formed and adapted to recede past said lug for a succeeding portion after the chase has been moved, the lug and engaging part being relatively inclined to facilitate the riding of ⁹⁵ 95 the engaging part beneath the lug.

9. In a machine of the character described, the combination with a chase, of means for propelling and guiding the same into printing position, the chase having a lug depending from its lower portion, and the propelling means having an engaging part adapted to cooperate with said lug to create a moving engagement therebetween.

10. In a machine of the character de- ¹⁰⁵ 105 scribed, the combination with a chase, of means for propelling and guiding the same into printing position, the chase having a lug depending from its lower portion, and the propelling means having an engaging ¹¹⁰ 110 part adapted to cooperate with said lug to create a moving engagement therebetween, said lug having a recess in its end face the engaging wall of which is inclined downwardly and towards the engaging part of ¹¹⁵ 115 the propelling means whereby in the movement of the chase a downward force is created tending to hold the chase in place.

11. In a machine of the character de- ¹²⁰ 120 scribed, instrumentalities for guiding and placing a chase in printing position, the guiding means having upstanding walls and overhanging flanges, and the chase having elongated spring arms constituting resilient means at its opposite sides, the spring arms ¹²⁵ 125 and overhanging flanges acting to firmly hold the chase in operative position relative to the guiding means.

12. In a machine of the character de- ¹³⁰ 130 scribed, instrumentalities for guiding and

placing a chase in printing position, the guiding means having upstanding walls and overhanging flanges, the chase having elongated spring arms constituting resilient means at its opposite sides acting to firmly hold the chase in position with reference to said upstanding walls, and propelling means having in part a spring element tending to hold the chase in firm position against said overhanging flanges.

13. In a machine of the character described, a guideway having a straight horizontal portion provided with overhanging retaining flanges, chases adapted to travel said guideway below said overhanging flanges, and an upwardly curved continuation of the guideway to feed chases into the latter, the mouth of the horizontal portion of the guideway at the termination of the upwardly curved portion being flared to facilitate passage of the chases from the curved feeding portion into the horizontal portion of the guideway.

14. In a machine of the character described, horizontally disposed guiding means for chases, chases therein each having an engaging part, the guiding means having a slotted bottom portion of approximately the length of a pair of chases, and a reciprocating propelling means positioned in said slot having a releasable part for cooperating with the engaging part of each chase.

15. In a machine of the character described, horizontally disposed guiding means for chases, chases therein each having an engaging part, the guiding means having a slotted bottom portion, propelling means positioned in said slot having a releasable part cooperating with the engaging part of each chase, and means for moving said propelling means back and forth to engage successive chases.

16. In a machine of the character described, horizontally disposed guiding means for chases, chases therein each having an engaging part, the guiding means having a slotted bottom portion, propelling means positioned in said slot having a releasable part cooperating with the engaging part of each chase, and means for moving said propelling means back and forth to engage successive chases, including a spring for retracting the same to normal position, and means opposed to said spring for influencing movement in an opposite direction when propelling a chase.

17. In a machine of the character described, horizontally disposed guiding means for chases, chases therein each having an engaging part, the guiding means having a slotted bottom portion, propelling means positioned in said slot having a releasable part cooperating with the engaging part of each chase, and means for moving said propelling

means back and forth to engage successive chases, including a spring for retracting the same to normal position, and means opposed to said spring for automatically influencing movement in an opposite direction when propelling a chase and controlling the to-and-fro actions of the propelling means.

18. In a machine of the character described, guiding means for chases, chases therein having an engaging part, propelling means having a releasable part cooperating with the engaging part of each chase, and means for moving said propelling means back and forth to engage said successive chases including a spring for retracting the same to normal position, and means opposed to said spring for influencing movement in an opposite direction including a slidable member, a chain or the like connecting the same with the chase propelling means, and a spring-held actuating member adapted to cooperate with the slidable member to shift the same.

19. In a machine of the character described, guiding means for chases, chases therein having an engaging part, propelling means having a releasable part cooperating with the engaging part of each chase, and means for moving said propelling means back and forth to engage said successive chases including a spring for retracting the same to normal position, and means opposed to said spring for influencing movement in an opposite direction including a slidable member, a chain or the like connecting the same with the chase propelling means, and a spring-held actuating member adapted to cooperate with the slidable member to shift the same, the slidable member having a depending stop, and a bevelled releasing device in the path of movement of the stop to free the same from the shifting actuating member.

20. In a machine of the character described, guiding means for chases, chases therein having an engaging part, propelling means having a releasable part cooperating with the engaging part of each chase, and means for moving said propelling means back and forth to engage said successive chases including a spring for retracting the same to normal position, and means opposed to said spring for influencing movement in an opposite direction including a slidable member, a chain or the like connecting the same with the chase propelling means, and a spring-held actuating member adapted to cooperate with the slidable member to shift the same, the slidable member having a depending stop, and a bevelled releasing device in the path of movement of the stop to free the same from the actuating member, to permit the retracting spring to restore the parts to normal position, and means inter-

posed between the depending stop of the slideable member and the actuating member acting in one direction to cause the actuating member to engage the stop and in another direction to permit restoration of the parts to normal relationship.

21. In a machine of the character described suitable guiding and positioning means for chases, combined with a plurality 10 of chases operatively associated therewith, and means for effecting progressive feeding movement of the chases including a movable shifting mechanism adapted to successively engage the chases, and a stationary 15 controlling device in the path of movement of

said shifting mechanism for causing the shifting of a chase thereby.

22. In a machine of the character described suitable guiding and positioning means for chases, combined with a plurality 20 of chases operatively associated therewith, and means for effecting progressive feeding movement of the chases including a movable shifting mechanism adapted to successively engage the chases, and a stationary spring 25 supported controlling device in the path of movement of said shifting mechanism for causing the shifting of a chase thereby, substantially as and for the purpose set forth.

THOMAS C. SPELLING.
